UNITED STATES PATENT OFFICE.

ABEL P. HOLCOMB AND AUGUST HEINE, OF SILVER CREEK, NEW YORK.

CENTRIFUGAL FLOUR-BOLT.

SPECIFICATION forming part of Letters Patent No. 280,622, dated July 3, 1883.

Application filed January 17, 1883. (No model.)

To all whom it may concern:

Be it known that we, ABEL P. HOLCOMB and AUGUST HEINE, of Silver Creek, in the county of Chautauqua and State of New York, 5 have invented new and useful Improvements in Centrifugal Flour-Bolts, of which the following is a specification.

This invention relates to certain improvements in that class of bolting-machines generally known as "centrifugal" bolts, which are provided with a rotating cylinder and rotating beaters arranged within the cylinder, whereby the material to be bolted is driven against all parts of the cylindrical bolting-surface.

15 Our invention has the object to improve the operation of this class of machines; and our invention consists of the improvements which are hereinafter more fully described, and pointed out in the claims.

20 This invention relates to certain improvements which were described and shown in our former Letters Patent, No. 271,846, dated February 6, 1883, but not specifically claimed therein.

25 In the accompanying drawings, consisting of two sheets, Figure 1 is a longitudinal sectional elevation of our improved bolting-machine. Fig. 2 is an elevation of the front end of the machine, with the feed mechanism in section. Fig. 3 is an elevation of the rear end of the machine. Fig. 4 is a cross-section of the machine, looking rearward. Fig. 5 is a cross-section in line $x-x$, Fig. 1. Fig. 6 is an enlarged longitudinal section of the feed end 30 of the bolting-cylinder. Fig. 7 is a cross-section in line $y-y$, Fig. 1. Fig. 8 is a front elevation of the disintegrating-head arranged within the bolting-cylinder.

Like letters of reference refer to like parts 40 in the several figures.

A represents the frame of the machine, and A' the inclosing-casing, which is made airtight as nearly as practicable.

B represents the bolting-cylinder, which is 45 composed of two heads, D D', connected by stay-bolts, rods, or bars d , and which is covered with bolting-cloth b , of suitable mesh, supported by suitable rings, d' . The head D of the feed end of the bolting-cylinder is provided with a hollow journal, e , which turns in

a bearing, e' , secured to the frame A, and the head D', at the tail end of the bolting-cylinder, is provided with a similar hollow journal, e'' , which turns in a bearing, e''' .

f represents the rotating beaters, which are 55 arranged in the bolting-cylinder and secured to rings f' . The latter are attached by arms f'' to a shaft, f''' , which passes through the hollow journals e e'' , and is supported in bearings f^4 f^5 .

The cylinder B is slightly inclined from the head D toward the head D', to cause the material to pass slowly through the cylinder; or the beaters f may be arranged spirally to propel the material through the cylinder in the 65 proper direction; or both means may be employed together to impart the necessary movement to the material.

g represents a rotating spiral brush, which is arranged transversely at the head of the 70 machine, and g' is the trough in which the brush rotates, and which is constructed of wire-cloth or perforated metal, having openings which permit the passage of the material to be bolted, but retain all larger impurities, 75 such as dough-balls, nails, stones, &c. The latter pass through an opening, g'' , at the end of the perforated trough into a receptacle, G, which is provided with suitable slides, through which the accumulated material can be removed from time to time.

g^3 represents the feed-spout, through which the material to be bolted is introduced into the trough g' .

i represents a screw-conveyer arranged underneath the perforated trough g' , and i' is the trough of the conveyer i , which receives all the fine material which has passed through the openings of the perforated conveyer-trough g' . The conveyer i delivers the fine material to the feed-spout i'' . The spiral brush serves to disintegrate the material and forces the fine particles through the perforations of the trough g' into the trough i' below, while it conveys the coarse substances to the discharge-orifice without injury to the clothing of the perforated trough. The feed-spout i'' discharges the material into a conical hood, J, which is secured with its large end to the outer side of the head D, so as to turn with the cylinder B, and which 90 95 100

turns with its small end on a fixed collar or short sleeve, *j*, which is secured to the adjacent portion of the casing *A'*. The hood *J* is fitted so snugly on the collar *j* that but little air can leak into the cylinder *B* through this joint, and, if desired, this joint may be further protected by a ring of india-rubber or leather.

The head *D* is composed of an annular plate, *k*, having a marginal flange, *k'*, to which the ticking of the bolting-cloth is secured. This plate *k* is provided with a central circular opening, *k''*. On the outer side of the plate *k* are formed radial ribs or arms *k''*, which have their outer ends beveled to fit against the inner side of the head *J*, and which extend inwardly across the central opening, *k''*, to a curved or conical deflector, *L*, which surrounds the inner end of the journal *e*, and projects with its small end into the opening *k''*. The plate *k*, ribs *k''*, deflector *L*, and journal *e* are preferably cast in one piece. The deflector *L* does not extend to the hood *J*, so that an annular opening, *l*, is formed between the edge of the deflector and the hood. The material delivered into the hood *J* by the spout *i* slides through the annular opening *l* against the outer side of the plate *k* and is picked up by the ribs *k''*, and elevated by the same until the ribs in rotating assume an inclination, which causes the material resting on the same to slide off, when the material strikes against the inner side of the deflector *L*, and is thereby deflected through the central opening, *k''*, into the bolting-cylinder *B*.

l' is a disk or circular plate secured to the shaft *f''*, near the inner side of the opening *k''*, and provided with one or more circular rows of pins or beaters, *l''*, arranged opposite the edge of the feed-opening *k''*. The material entering the bolting-reel through the opening *k''* strikes against the rotating disk *l'*, near its center, and is driven outwardly by the centrifugal force between the rotating pins *l''*, which disintegrate the material and distribute the same in a spray over the inner surface of the surrounding portion of the bolting-cylinder.

In passing through the cylinder *B* from the head *D* to the head *D'* the material is thrown by the beaters *f* against the bolting-cloth of the cylinder *B*, and thereby separated, the flour or fine and heavy material passing through the meshes of the bolting-cloth into the surrounding inclosed space, while the lighter particles remain in the bolting-cylinder and finally arrive at the head *D'*. The latter is provided on its inner side with radial ribs *m*, and with a central discharge-opening, *m'*, which is surrounded by a short collar, *m''*, extending rearwardly.

m'' is a curved or conical deflector, having its convex side turned rearwardly and connected with the inner ends of the ribs *m* and the inner end of the journal *e''*. The material which reaches the inner side of the head *D'* is lifted by the ribs *m* until the increasing incli-

nation of the ribs causes the material to slide off, when it strikes the convex side of the deflector *m'*, and is thereby deflected rearwardly and discharged through the opening *m'* into a receptacle, *M*. The latter is arranged between the head *D'* and the rear wall of the casing *A'*, and projects with its lower end through said casing. This receptacle is provided with two automatic discharge-valves, *n n'*, which prevent the entrance of the external air, and which open at different times under the pressure of the accumulated material and permit the discharge of the material without admitting air to the cylinder *B*.

It is very important to avoid the admission of air to the cylinder, as the presence of air-currents interferes with the operation of bolting; and it is especially important to avoid the admission of air at the tail end of the cylinder, because ingoing currents of air would carry back into the cylinder the light floating bran-specks, which would result in rendering the flour specky.

O represents an opening formed in the head-board of the casing *A'*, within the collar *j*, for the purpose of admitting air to the head of the bolt when required. The opening *O* is provided with a slide, *o'*, whereby it may be entirely closed, if desired, or its size may be regulated and the ingoing air-currents controlled. By admitting air at the head of the bolt the air passes through the bolt from the head toward the tail, and the return of the specks from the tail portion of the bolt toward the head is thereby prevented.

P P' represent two screw-conveyers arranged below the bolting-cylinder *B*, one above the other, and provided in their troughs with a suitable number of openings controlled by slides *p*, so that the bolted material can be drawn off at any desired point.

q represents the driving-pulley, secured to the end of the shaft *f''*, and *q'* is an endless belt which runs around a small pulley, *q''*, on the shaft *f''*, and a larger pulley, *q'''*, on the shaft of the lower conveyer, *P'*, whereby the latter is rotated.

r represents an endless belt which runs around a small pulley, *r'*, on the shaft of the lower conveyer, *P'*, and a larger pulley, *r''*, on the hollow journal *e''*, whereby the cylinder *B* is rotated from the conveyer *P'* with much less speed than the beaters. The upper conveyer, *P*, is driven from the lower conveyer, *P'*, by gear-wheels *s s'*, and the conveyer *i* is driven from the conveyer *P* by means of a counter-shaft, *s''*, and an endless belt, *s'''*. The spiral brush *G* is driven from the conveyer *i* by gear-wheels *s'' s'''*.

T T' represent adjustable transverse partitions arranged in the hopper or lower portion of the casing, above the conveyer *P*, for the purpose of more perfectly separating the different grades of material which are bolted through the bolting-cloth. These partitions are provided with rods *t t'*, which extend

through one of the end walls of the casing, and whereby the partitions can be adjusted.

U represents a blast-fan, which is actuated by a belt, u, from the beater-shaft f³.

5 u' represents the blast-pipe of the fan, arranged parallel with the side of the cylinder B, in close proximity therewith, and provided on the side adjacent to the cylinder with perforations, whereby the air which is driven into 10 the pipe by the blast-fan is delivered in jets upon the surface of the bolting-cylinder, whereby the meshes of the latter are freed from any material which may tend to adhere to the same. The distance between the cylindrical 15 surface of the bolt and the perforated air-pipe remains the same during the revolutions of the bolt, and the air-blast operates, therefore, uniformly upon all parts of the bolting-cloth. The bolting-cloth is applied to the bolting-cylinder in two cylindrical sections, which may each be composed, if desired, of one or more 20 different grades of cloth.

We claim as our invention—

1. The combination, with a flour-bolt composed of a revolving bolting-cylinder and revolving beaters arranged within such cylinder, of a preliminary disintegrating and separating mechanism composed of a spiral brush and a perforated trough in which the brush

rotates, and means whereby the fine material 30 which is driven through the perforations of the casing is conducted into the flour-bolt and the coarse material excluded from the flour-bolt and discharged separately, substantially as set forth.

2. The combination, with a revolving bolting-cylinder, B, and revolving beaters f, of a head, D, arranged at the feed end of the bolting-cylinder, and provided with a central opening, k², ribs k³, and a deflector, L, whereby the material is fed into the bolt at or near 40 its axis, a hood, J, and a collar, j, substantially as set forth.

3. The combination, with a rotating bolting-cylinder and rotating beaters, of a feed device 45 consisting of a head, D, provided with a central opening, k², ribs k³, a deflector, L, and hood J, whereby the material is fed into the bolt near its axis, and a discharge device consisting of a head, D', having a central opening, m², ribs m³, and a deflector, m³, whereby 50 the coarse residue is discharged from the bolt, substantially as set forth.
